FLANK CINCH ADAPTER

Jerry L. Copley, 795 S. Pennsylvania St.,
Denver, Colo. 80209

Filed May 29, 1968, Ser. No. 12,115

Term of patent 14 years

U.S. Cl. D30—19
Int. Cl. D30—03

FIG. 1.

FIG. 2.

FIG. 3.

FIGURE 1 is a front view in elevation of the flank cinch adapter showing my new design, the rear view being a mirror image thereof;

FIGURE 2 is a plan view thereof; and,

FIGURE 3 is an end view.

A representation of a saddle is depicted in dotted lines in FIGURE 1 for purposes of illustration.

I claim:

The ornamental design for the flank cinch adapter, as shown and described.
